UNITED STATES PATENT OFFICE.

HENRY A. WISE WOOD, OF NEW YORK, N. Y., AND CONRAD NORDFORS, OF JERSEY CITY HEIGHTS, NEW JERSEY, ASSIGNEES, BY MESNE ASSIGNMENTS, TO WOOD NEWSPAPER MACHINERY CORPORATION, OF NEW YORK, N. Y., A CORPORATION OF VIRGINIA.

PLATE-CLAMPING DEVICE FOR PRINTING-PLATE CYLINDERS.

1,321,268.

Specification of Letters Patent. Patented Nov. 11, 1919.

Application filed March 6, 1912, Serial No. 681,923. Renewed April 11, 1919. Serial No. 289,465.

To all whom it may concern:

Be it known that we, HENRY A. WISE WOOD and CONRAD NORDFORS, citizens of the United States, said Wood residing at New York, in the county of New York and State of New York, and said NORDFORS residing at Jersey City Heights, county of Hudson, and State of New Jersey, have invented a new and useful Plate-Clamping Device for 10 Printing-Plate Cylinders, of which the following is a specification.

This invention relates to that type of printing cylinders on which a plurality of plates are mounted, preferably in rows.

15 The principal objects of the invention are to provide improvements in the plate clamp operating mechanism, whereby the plate clamps at each end of the cylinder will be capable of being simultaneously withdrawn 20 from clamping position or moved back substantially to clamping position very rapidly and individually adjusted more minutely; to provide a construction in which the plate clamps are locked in adjusted position so as 25 to avoid all danger of the plates becoming loose in operation; to provide means whereby the adjusting means cannot be interfered with by the more rapidly operating plate moving devices, and to provide improvements 30 in the details of the plate clamping and clamp locking mechanism; and also in the construction of the cylinder itself. Further objects and advantages of the invention will appear hereinafter.

35 Reference is to be had to the accompanying drawings in which—

Figure 1 is an end view of a printing plate cylinder provided with a preferred embodiment of this invention;

40 Fig. 2 is a sectional view of one end of the same on the broken line 2—2 of Fig. 1;

Fig. 3 is a longitudinal sectional view of a portion of the cylinder taken diametrically at a point between the plate clamping de-

45 vices;

Fig. 4 is an enlarged view similar to the bottom of Fig. 1; and

Figs. 5, 6 and 7 are diagrammatic end views showing three different positions of the parts. 50

It has been found in practice that the printing plates mounted on the plate cylinder in printing presses occasionally become dislodged owing to the clamps working loose. This is a very serious accident as it 55 usually happens when the press is operating at full speed and is liable to break the machine. The clamps which have been used heretofore are not capable of being absolutely locked in clamping position and they 60 also have the disadvantage of requiring a comparatively long operation for the purpose of loosening and withdrawing them individually, so that the plates can be removed and replaced and then adjusting them 65 up to proper position. It is for remedying these defects mainly that this invention is designed, and it involves a plate clamping device which is capable of rapid motion to bring a plurality of clamps up substantially 70 to clamping position, leaving them so that the fine adjustments can be secured independently; also a positive locking device for the clamps to hold them in their adjusted positions, an improved form of clamp 75 suitable for operating in this way, and an improved printing cylinder to avoid the last mentioned difficulty.

Referring to the drawings, a printing plate cylinder shaft 10 is shown having 80 solidly fixed thereon a solid printing plate cylinder 11 comprising a uniform and solid body of metal reaching from the shaft to the circumference and having a comparatively great weight, so that as the cylinder passes 85 the point at which a row of plates move into or out of contact with the impression cylinder the momentum of the cylinder will be sufficient to prevent any sudden change in the speed of rotation. 90

The cylinder is shown as provided with the usual clips 12 for holding plates 14 in rows. At the ends are plate clamps 15 each shown as constituting substantially a quarter

circle on the end of the cylinder. Each plate clamp has an outer cylindrical portion provided with an inclined edge 16 for gripping the edge of the plate. It is shown also as 5 having an end portion 17 extending over substantially a quarter of the end of the cylinder and a curved inner tongue 18 fitting in a groove in the end of the cylinder. It also has a projecting lip 19 on the inner 10 edge to engage under a ledge 190 on the cylinder to hold the clamp firmly against the printing plate, and especially to keep the bevel 16 in proper position to hold down the beveled edge of the plate.

15 It will be understood, of course, that although four of these clamps are shown, any other desired number can be employed. Between each pair of them is located a part of a clamp operating means comprising a 20 stud 20 fixed in the end of the cylinder, a gear 21 rotatable on the stud, and a plate 22 fixed with respect to the gear and having a non-circular projection 23 for receiving a wrench or the like for the purpose of rotating the plate and gear. At certain nearly 25 opposite points on the gear it is mutilated, that is, provided with a space 24 without teeth but formed mainly on a circle concentric with the pitch circle. This space has 30 a portion cut away at 25 for clearance as will appear hereinafter. This plate 22 is provided with two notches 26 located in position to register with the spaces 24.

35 Meshing with the teeth of the gear 21 are a pair of gears 27 each having a space 28 in which it is mutilated. This mutilation consists of a continuous curved surface which substantially fits the surface 24 of the gear 21. It will be seen, therefore, that 40 when the surfaces 24 and 28 are in contact, as shown at the bottom of Fig. 1, the gears 27 cannot be turned, and that the gear 21 can be turned in one direction but not in the other, on account of one of its teeth projecting in the way of the first tooth of the gear 27. On one side however the cut away part 25 provides the necessary clearance to permit rotation in the other direction.

45 To each of these gears 27 is fixed a worm 29 which engages the plate clamp 15 to be operated. This worm is of comparatively quick pitch and it will be obvious that the rotation of the gear 21 when the teeth are in mesh with the gears 27 will cause the two 50 plate clamps on opposite sides of the stud 20 to be advanced rapidly toward or from clamping position.

The parts are so designed that the surfaces 55 24 and 28 register before the clamp comes fully into position to grip a plate and the actual gripping action is designed to be performed by the following mechanism.

60 Concentrically mounted with respect to each of the worms 29 and gears 27, but rotatable independently thereof, is a screw 30

entering a nut 31 fixed in the cylinder. This screw is provided on its outer end with a non-circular portion 32 by which it is rotated. It also has fixed thereon a plate 33 which is of a general circular form but has a 70 notch 34 adapted to fit the circumference of the plate 22 when in the position shown in Fig. 5. The screw is provided with a fixed collar 35 at the end of the worm 29. Thus the worm and its gear 27 are rotatable on the 75 screw 30 between this collar and the plate 33.

The screw 30 is connected with the plate clamp by a screw pin 36 entering a circumferential slot 37 which communicates with a longitudinal slot 38 in the screw. When the 80 parts are in the position shown in Fig. 7 the pin is in the circumferential slot and consequently the rotation of the screw will advance the plate clamp.

The operation of clamping a plate is as 85 follows: Starting with the clamps withdrawn and the circular plates in the position shown in Fig. 5, it will be obvious that the plates 33 and screws 30 cannot be rotated. The rotation of the gear 21 in one 90 direction causes both worms 29 to turn and the clamps to be moved up toward clamping position. But when the gear 21 moves to a position shown in Fig. 4 its rotation in that direction is stopped by the tooth at the end 95 of the space 24.

When it is time to begin the actual clamping, the pin 36 registers with the groove 37. Sufficient clearance is allowed in this groove 100 for the free rotation of the end of the pin 36 therein, and consequently the edge of the pin 36 and the edge of the groove 37 never come into intimate contact. However, the shoulder of the collar 35 acting against the corresponding shoulder of the worm 29, 105 which in this position really forms part of the clamp, transmits the pressure to the clamp. The object of the horizontal groove in the screw 30 is to keep the screw from turning on account of friction from the 110 worm 29 while the clamp is being brought into clamping position. The circular part of this groove makes it possible to turn the screw 30 for the purpose of clamping.

Figs. 1, 2 and 6 show the parts in positions that they assume when the plate clamps have been moved up by the worm and are locked against further rotation of the gear 21 and worm 29 in the same direction. However, the screws 30 are no longer 120 locked against rotation, owing to the fact that the parts are so designed that when the notches 34 come into the position shown in Fig. 6, the pin 36 comes to the end of the longitudinal slot 38 and registers with the 125 circumferential slot 37 which permits rotation of the screw.

Now in order to secure the necessary adjustment of the plate clamps, the screws are turned until the clamps grip the plates 130

properly. This is now possible because the notches 26 and 34 register as in Fig. 6. But this adjustment brings the plates 33 into the position shown in Fig. 7 which shows a 5 position in which the plate 22 is locked but the plates 33 are still free to rotate for the finer adjustment of a plate clamp. When it is desired to release the worm, the screw 30 is turned until the pins 36 reach the wall 10 of the longitudinal groove 38 when the notches 34 automatically come into registration with the notches 26, as shown in Fig. 6. Then the plate 22 is free and can be rotated.

15 It will be understood of course that when the plate 22 is locked by the plates 33 the gears 27 are also locked by the mutilated portions 24 and 28 being in contact with each other. It will be seen, therefore, that 20 the quick moving worm for operating the plate clamps back and forth rapidly is effectively and absolutely locked against motion of any kind after any adjustment has been made for the purpose of actually 25 clamping the plates. In order to permit the withdrawal of this quick acting part, the clamps all have to be moved back from the plates a certain distance by turning the screws 30, and thereafter all the clamps can 30 be moved back very rapidly, thus saving considerable time.

Although we have illustrated and described a preferred embodiment of the invention, we are aware that many modifications can be made therein by any person skilled in the art without departing from the scope of the invention as expressed in the claims. Therefore, we do not wish to be limited to the details of construction herein 35 shown and described, but what we do claim 40 is:

1. The combination with a printing plate cylinder, of a series of plate clamps thereon arranged edge to edge around the circumference of the cylinder in pairs, means between the clamps of each pair for simultaneously operating the two clamps of that pair comprising a worm for each clamp, and means concentric with said worms for there- 45 after adjusting each clamp of a pair independently.

2. The combination with a printing plate cylinder having a plate clamp, of means for rapidly moving the plate clamp toward or 50 from clamping position, and means concentrically connected with said moving means for securing a finer adjustment of the plate clamp in either direction.

3. The combination with a printing plate 55 cylinder having a plate clamp, of means for moving the plate clamp toward or from clamping position, means for securing a finer adjustment of the plate clamp, and means for holding the adjusting means posi- 60 tively locked during the time when said

moving means is in operation and automatically releasing it upon the completion of the motion of said moving means.

4. The combination with a printing plate cylinder having a plate clamp, of means for 70 moving the plate clamp toward clamping position, means for securing a finer adjustment of the plate clamp, and means for holding said moving means positively locked during the time when the adjusting means 75 is in operation and automatically releasing it upon the completion of the adjustment.

5. The combination with a printing plate cylinder having a plate clamp, of means for 80 rapidly moving the plate clamp toward or from clamping position, means for securing a finer adjustment of the plate clamp, and means for preventing the operation of each 85 of said means whenever the other is in operation.

6. The combination with a printing plate cylinder, of a plate clamp therefor, rotary means for moving the plate clamp toward and from clamping position, means for limiting this movement of the plate clamp to a 90 definite limit, and means rotatable on the same axis for thereafter adjusting the plate clamp farther in the same direction.

7. The combination with a printing plate cylinder and a plate clamp therefor, of 95 means for moving the plate clamp toward clamping position, means for limiting the operation of the first named means, means for thereafter adjusting the plate clamp farther in the same direction, and means 100 whereby the adjusting means is prevented from operating during the operation of the first named means.

8. The combination with a printing plate cylinder and a plate clamp therefor, of 105 means for moving the plate clamp toward clamping position, means for limiting the operation of the first named means, means for thereafter adjusting the plate clamp farther in the same direction, and means whereby the first named means is prevented from 110 operating during the operation of the adjusting means.

9. The combination with a printing plate cylinder and a plate clamp therefor, of 115 means for moving the clamp rapidly up to a certain position, means for thereafter adjusting the plate clamp, and means controlled by said moving means for rendering said adjusting means inoperative during 120 said rapid motion of the plate clamp.

10. The combination with a printing plate cylinder and a plate clamp therefor, of means for moving the clamp rapidly up to a certain position, means which is rendered inoperative during said motion for thereafter adjusting the plate clamp, and means for locking both the moving and the adjusting means in their adjusted positions. 125

11. The combination with a printing plate 130

cylinder, of a plurality of plate clamps therefor, means for simultaneously moving said clamps inwardly toward clamping position, means for thereafter individually adjusting each clamp, and means whereby said adjusting means is rendered inoperative by said moving means.

12. The combination with a printing plate cylinder, of a pair of plate clamps therefor, means for simultaneously moving said clamps inwardly toward clamping position, means for thereafter individually adjusting each clamp, and means operated by the moving means for simultaneously locking both the adjusting means to render them incapable of being operated.

13. The combination with a printing plate cylinder, of a pair of plate clamps therefor, means for simultaneously moving said clamps inwardly toward clamping position, means for thereafter individually adjusting each clamp, and means connected with the adjusting means to be operated therewith whereby the moving means can move the plates near to a predetermined position and is then locked against further operation in that direction.

14. The combination with a printing plate cylinder, of a pair of plate clamps therefor, means for simultaneously moving said clamps inwardly toward clamping position, means for thereafter individually adjusting each clamp, means whereby the moving means can move the plates near to a predetermined position and is then locked against further operation in that direction although free to move in the other direction, and means whereby until the moving means reaches said predetermined position, the several adjusting means will be locked positively against operation.

15. The combination with a printing plate cylinder, and a pair of plate clamps therefor, of a stud located between said clamps, means connected with said stud for advancing both of said clamps to a predetermined position, means for stopping the operation of said means when the clamps have reached said predetermined position, and means for further adjusting each clamp individually.

16. The combination with a printing plate cylinder, and a pair of plate clamps therefor, of a stud located between said clamps, means connected with said stud for advancing both of said clamps to a predetermined position, means for stopping the operation of said means when the clamps have reached said predetermined position, means for further adjusting each clamp individually, and means for rendering said adjusting means for each clamp inoperative while the moving means is in operation.

17. The combination with a printing plate cylinder, and plate clamps therefor, of a

rotatable member located substantially between two of said plate clamps, means adapted to be rotated by said member for operating the two clamps between which said means is located, and means for limiting the operation of said clamps and for adjusting each clamp independently thereafter.

18. The combination with a printing plate cylinder and a pair of plate clamps therefor, of means located between the clamps for simultaneously advancing both clamps, said means comprising a rotatable mutilated gear, a mutilated gear having means for advancing each clamp and meshing with the first named gear, and a screw concentric with each of said last named mutilated gears for adjusting each plate clamp independently thereof.

19. The combination with a printing plate cylinder and a plurality of plate clamps therefor, of means for simultaneously advancing said clamps, said means comprising a rotatable mutilated gear, a mutilated gear having means for advancing each clamp and meshing with the first named gear, a screw concentric with each of said last named mutilated gears for adjusting each plate clamp independently thereof, and means whereby said screw is prevented from rotating while the mutilated gears are in operation.

20. The combination with a printing plate cylinder and a plurality of plate clamps therefor, of means for simultaneously advancing said clamps, said means comprising a rotatable mutilated gear, a mutilated gear having means for advancing each clamp and meshing with the first named gear, a screw concentric with each of said last named mutilated gears for adjusting each plate clamp independently thereof, and means whereby said screw is prevented from operation until the mutilated gears come to a position in which they are locked against further rotation, said screws then being capable of turning to further adjust the said plate clamps.

21. The combination with a printing plate cylinder, and a plurality of plate clamps thereon, of a rotatable gear, a circular plate fixed thereon, said gear being mutilated, the plate having a notch in its edge, a worm connected with each of said plate clamps, a gear fixedly mounted with respect to each worm and meshing with the first named gear and provided with a mutilated portion adapted to fit the mutilated portion of the first named gear to lock it in position, an adjusting screw concentric with each worm and connected with the plate for adjusting it, said adjusting screw being rotatable independently of the worm and having a plate thereon with a notch therein fitting the circumference of the first named plate.

22. The combination with a printing plate

cylinder and a plurality of plate clamps thereon, of a rotatable gear, a circular plate fixed thereto, the plate having a notch in its edge, a worm connected with each of said 5 plate clamps, a gear fixedly mounted with respect to each worm and meshing with the first named gear, an adjusting screw concentric with each worm and connected with the plate for adjusting it, said adjusting 10 screw being rotatable independently of the worm and having a plate thereon with a notch therein fitting the circumference of the first named plate, said screw having a longitudinal slot provided with a circumferential slot at the end thereof communicating therewith, and a pin on the plate adapted to enter said slots, said slots being so located that when the worm is operating 15 the pin is in the longitudinal slot and when 20 the mutilated parts of the gears and plates come into registration the pin will register with the circumferential slot to permit the screw to be turned thereafter.

23. The combination with a printing plate 25 cylinder, of a series of plate clamps thereon arranged around the circumference of the

cylinder in pairs, means for simultaneously operating the two clamps of a pair, and means for thereafter adjusting each clamp of a pair independently, said last named means 30 also constituting means for locking the first named means against further operation in either direction.

24. The combination of a printing plate cylinder having a longitudinal ledge and a 35 groove near the end, and a plate clamp therefor having a beveled edge and provided with a lip under said beveled edge in position to pass under the ledge, when in clamping position, and an inner tongue adapted to 40 extend into said groove whereby the beveled edge of the clamp will be held positively against the plate to be clamped.

In testimony whereof we have hereunto set our hands, in the presence of two sub- 45 scribing witnesses.
